No. 823,685.

PATENTED JUNE 19, 1906.

C. E. HOWARD.
MAT CUTTING BOARD.
APPLICATION FILED JAN. 20, 1906.

UNITED STATES PATENT OFFICE.

CHARLES E. HOWARD, OF PATERSON, NEW JERSEY.

MAT-CUTTING BOARD.

No. 823,685.

Specification of Letters Patent.

Patented June 19, 1906.

Application filed January 20, 1906. Serial No. 296,949.

To all whom it may concern:

Be it known that I, CHARLES E. HOWARD, a citizen of the United States, residing in Paterson, county of Passaic, State of New Jersey, have invented certain new and useful Improvements in Mat-Cutting Boards; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention is an improvement in boards for use in cutting picture-mats and the like; and it has for its object to provide a device of this nature which shall be less expensive in construction and more easily and accurately manipulated than others of its kind at present in use.

To this end my invention consists, broadly, in a base-board having an abutment for one side of the sheet to be cut, guideways arranged at right angles to said abutment, guides arranged to travel on said guideways, and a cutting-bar movable with said guides over the base-board.

In the accompanying drawings, Figure 1 is a top plan view of my invention. Fig. 2 is a side view thereof; Fig. 3, a side view of the front portion thereof enlarged, showing certain portions in section. Fig. 4 is a front view of the invention enlarged, also showing certain portions in section. Fig. 5 is a plan view of one end of the cutting member, and Fig. 6 shows one of the guides.

The base-board *a* is preferably made of a series of sections dovetailed together edge to edge, as best shown in Fig. 3. The sides of the board are preferably squared up so as to make the same a true rectangle.

b is a strip which is secured along the outer side of one of the end sections of the base-board and whose top edge projects slightly above it, thereby forming an abutment *c*, against which one edge of the mat to be cut is placed. Along the two sides or edges of the base-board which are at right angles to the strip *b* are secured, as by screws *d*, other strips *e*, which are preferably of metal and stand flush at the top and bottom with the top and under sides of the base-board. Just inside of each strip *e* the top face of the base-board is grooved, as at *f*, from the strip *b* to the rear side or edge of the base-board, and in

this groove is fitted a gage or rule *g*. Each gage or rule may be secured by screws *h*. The front portion of the upper face of the base-board is furthermore provided with a recess *i*, extending from one gage *g* to the other and having a width corresponding to the maximum width or depth of picture-mats ordinarily used. In this recess is arranged a sheet of plate-glass or the like *j*.

k is a cutting-bar lying crosswise of the base-board—*i. e.*, parallel of the abutment *c*—the edge thereof toward the abutment being beveled, as at *l*. This cutting-bar is adapted to be adjusted to and from the abutment *c* with reference to the gages *g*, and for this purpose its ends are formed as projections *m*, which rest in recesses *n* in guides *o*, each having lugs *p*, adapted to move in guideways *q*, formed in the strips *e*, and each guide also having a screw *q'*, whose shank projects through the guideway *q* and whose head works in a groove *r*, into which said guideway opens, said groove being formed on the inside of the strip *e*. Each guide may be fixed at any desired position by a wing-nut *s* on its screw *q'*, which acts with the head *r* of the said screw to clamp the guide and strip together.

I prefer to have the cutting-bar supported mainly by the top surface of the board, whereby its weight will contribute largely to hold the mat being cut firmly in position. The usual cleats *t* may be secured to the under side of the board.

In the use of the board the mat to be cut, which is assumed to have already had its outer edges cut to a true rectangle, is laid on the board under member *k* (which may be lifted from the guides *o* for this purpose,) with one edge squarely against the abutment *c*. The cutting-bar is then adjusted to a distance from the abutment corresponding to the width or depth of the mat to be cut, whereupon a knife is drawn along the beveled edge of the cutting-bar, thereby cutting one side of the mat. The mat is then withdrawn and reintroduced with another side against the abutment *c* and the cutting operation repeated, and so on. Should the plate *j* become broken or damaged, it may be removed by first removing one of the gages *g*, so that convenient access to the plate may be had.

Having thus fully described my invention, what I claim as new, and desire to secure by Letters Patent, is—

In a device for use in cutting picture-mats

and the like, the combination of a base-board having an abutment for one side of the mat to be cut and two opposite sides thereof arranged at right angles to said abutment, 5 slotted strips arranged against said sides, screws arranged in the slots of said strips and having their heads projecting inwardly, a guide carried by each screw and having upwardly-projecting lugs, a wing-nut carried by 10 each screw and adapted to clamp each guide against the strip, and a cutting-bar engaged

loosely between the lugs of and adapted to move with, said guides, substantially as described.

In testimony that I claim the foregoing I 15 have hereunto set my hand this 18th day of January, 1906.

CHARLES E. HOWARD.

Witnesses:

JOHN W. STEWARD,
WM. D. BELL.
